E. E. ASHLEY, JR

COMBINED ELEVATOR SIGNAL CASING AND LENS

Filed June 18, 1926

Edward E. Ashley
INVENTOR

UNITED STATES PATENT OFFICE.

EDWARD E. ASHLEY, JR., OF DARIEN, CONNECTICUT, ASSIGNOR TO ELEVATOR SUPPLIES COMPANY, INC., A CORPORATION OF NEW JERSEY.

DESIGN FOR A COMBINED ELEVATOR SIGNAL CASING AND LENS.

Application filed June 18, 1926. Serial No. 18,084. Term of patent 14 years.

To all whom it may concern:

Be it known that I, EDWARD E. ASHLEY, Jr., a citizen of the United States, residing at Darien, in the county of Fairfield and State of Connecticut, have invented a new, original, and ornamental Design for a Combined Elevator Signal Casing and Lens, of which the following is a specification, reference being had to the accompanying drawings, forming part thereof, wherein—

Fig. 1 is a front elevation of the article showing my new design.

Fig. 2 is a vertical section of the same, taken on line 2—2 of Figure 1.

I claim:

The ornamental design for a combined elevator signal casing and lens as shown.

EDWARD E. ASHLEY, Jr.
